ATTACHMENT TRAY FOR A WHEELCHAIR

Harry Foster, P.O. Box 2056, San Rafael, Calif. 94902

Filed Feb. 5, 1969, Ser. No. 15,657

Term of patent 14 years

Int. Cl. D6—01

U.S. Cl. D33—3

FIG. 1

FIG. 3

FIG. 2

FIG. 6

FIG. 5

FIG. 4

FIG. 7

FIG. 1 is a perspective view of an attachment tray for a wheelchair showing my design;

FIG. 2 is a top plan view thereof;

FIG. 3 is a side elevation taken from the right-hand side of the tray as viewed in FIG. 2;

FIG. 4 is a side plan view taken from the left-hand side as viewed in FIG. 2;

FIG. 5 is a bottom plan view;

FIG. 6 is a rear plan view;

FIG. 7 is a front plan view.

I claim:

The ornamental design for an attachment tray for a wheelchair, as shown.
